UNITED STATES PATENT OFFICE.

JAMES M. EVANS, OF WESTPORT, CONNECTICUT, ASSIGNOR TO EVANS ENGINE COMPANY, INCORPORATED, A CORPORATION OF NEW YORK.

CARBURETER.

1,232,257.

Specification of Letters Patent.

Patented July 3, 1917.

Original application filed October 12, 1914, Serial No. 866,276. Divided and this application filed March 23, 1915. Serial No. 16,338.

To all whom it may concern:

Be it known that I, JAMES M. EVANS, a citizen of the United States, and a resident of Westport, in the county of Fairfield, State 5 of Connecticut, have invented certain new and useful Improvements in Carbureters, of which the following is a description.

My invention relates to a method for introducing a regulated quantity of liquid 10 fuel or other liquid into air or other gases, and for mixing such liquid, finely separated or vaporized, with such air or other gases in proper proportions; and the object of my invention is to provide a device, operating 15 on the rotary principle, whereby a regulated, constant and controllable quantity of the liquid will be supplied to the air or other gas and mixed in the proportions best adapted to the purpose for which such mixture is 20 intended to be used—whether for explosion in internal combustion engines, or other engines, apparatus or contrivances for generating power, or for enriching gases for illuminating, heating or other purposes, or 25 for obtaining a mixture of any liquid, finely separated or vaporized, with any gas for any purpose for which such an admixture of liquid and gas may be desired.

I accomplish these objects by a novel device 30 or arrangement, comprising a reservoir for fuel, a mixing chamber in which the liquid is delivered in measured charges and mixed with the air or gas and a rotary conveyor preferably in the form of a rotary 35 disk, having recesses formed in its periphery adapted to be opened in the reservoir and to receive the charges and to be closed in the mixing chamber, thereby forcibly ejecting and delivering the charges to said chamber.

Among the many purposes for which this device is adapted for use is the production of an explosive gas for the operation of internal combustion engines through the mixing 45 of a liquid fuel such as gasoline, kerosene, alcohol or any other volatile fluid hydrocarbon with atmospheric air in the proper portions for explosion in such engine; and I shall describe the operation of my device 50 with such an engine, but its use is by no means limited to such engines, although the

general method of operation with respect to other uses is similar to that about to be described.

In the drawing accompanying and forming part of this specification I have illustrated the preferred embodiment of my invention, and the construction, operation and advantages of my improved device will readily be understood from an explanation 55 of these drawings.

Referring to the drawings:

Figure 1 is a sectional view of my improved device shown attached to the intake pipe or manifold of a gas engine, which intake pipe or manifold constitutes the mixing 65 or carbureting chamber of the device.

Figs. 2 and 3 are sectional views of the improved device, showing the rotary disk employed to convey the liquid from the reservoir to the mixing chamber, in two operative 70 positioins.

Figs. 4 and 5 are detail views showing the mechanism employed for opening and closing the recesses at the periphery of the disk.

Referring now in detail to these drawings, the numeral 1 designates the liquid reservoir to which liquid is supplied through the pipe 2 and maintained preferably under slight head or pressure. The numeral 3 designates the mixing or carbureting chamber. The carrier of liquid from the reservoir to the chamber 3 comprises two plates 4 and 5 mounted on the shaft 6 and adapted to rotate between the fixed plates 7 and 8. The 80 plate 4 is provided with a flange 9 located on the face of the plate and extending slightly less than half around the plate. The plate 5 is also provided with a flange 10 and this flange is also located on the face of the plate 90 and extends slightly less than half around the same. When assembled, the flanges 9 and 10 each overhang the outer edge of the oppositely disposed plate and the two plates form a smooth disk, except for the recesses 95 at the ends of the flanges. Means are provided to move the two plates with respect to each other as they rotate on the shaft 6, in order that the adjacent ends of the flanges 9 and 10 may be made to move away from 10 each other in the liquid reservoir, thereby forming a recess into which the liquid flows

or is forced, and then to hold this relative position until the charge has been brought into the mixing or carbureting chamber where the ends of the flanges approach each other and forcibly eject the charge. To this end a bell-crank 11 is provided and disposed in a recess 12 in the plate 5. This bell-crank is provided with three arms. One of these, 13, is pivotally secured to the disk 4, and another, 14, is pivotally secured to the disk 5, while the remaining arm 15 is provided with a projection 16, adapted to move in the cam groove 17, formed in the fixed plate 8, as the bell crank as a whole rotates 10 with the disk. The cam groove 17 is so shaped that as the shaft 6 rotates and the adjacent ends 18 and 19 of the flanges 9 and 10 approach and enter the liquid reservoir, the plate 5 will move ahead of the plate 4 which is keyed on the shaft 6, and the ends 18 and 19 of the flanges will separate and form a recess as shown at 20 in Fig. 3. The liquid will be drawn or forced into the recess and will be carried around in the same 15 until the liquid is in the mixing or carbureting chamber 3. The cam groove will then act through the bell-crank and bring the ends together, thereby forcibly ejecting and spraying the liquid. In the continued rotation of the shaft 6, the recess is again opened in the reservoir, and the above cycle of operation is repeated. In the particular arrangement described, there are two sets of flange ends on each disk and the arrangement is 20 such that when one set of ends approaches in the mixing or carbureting chamber and closes the recess so as to eject and spray the liquid, the oppositely-disposed ends of the flanges separate and form a recess in the 25 liquid reservoir which is filled with a charge of fuel.

It will be observed that in the operation of the device, the component parts of the disk, which coöperate to form the recess, are sub- 30 merged in the liquid in closed relation. They then open, forming a recess of definite size into which a uniform and definite quantity of liquid is received. The component parts in which the recess is formed then pass 35 bodily through a passage and carry and deliver this measured charge directly into the mixing or carbureting chamber through which, in the example chosen for illustration, a current of air is passing on its way 40 to the engine. They then close and forcibly eject the liquid. The device therefore operates to deliver uniform and measured charges of liquid directly into the air in the mixing or carbureting chamber. This 45 method of operation renders my device free from any irregular action incident to the use of pumps with valves and to jet carburetors which depend upon suction or upon partial vacuum for operation. It is also independ-

ent of atmospheric pressure and does not require regulation, because of changes of atmospheric pressure. ⁶⁵

This application is a division of an application heretofore filed by me, Serial No. 866,276, filed October 12, 1914, and is filed in ⁷⁰ order that I may make claims relating specifically to the mechanism operating on the rotary principle, described above.

While I describe in this application only the preferred embodiment of my invention, ⁷⁵ I am aware that many modifications may be made by those skilled in the art, without departing from the scope of my invention.

What I claim is:

1. In combination in a device of the kind described, a reservoir chamber for liquid, a mixing chamber for the passage of air or other gas, a passage connecting the two chambers, a disk mounted in said passage and having a recess formed in its body, means for rotating said disk whereby the recess is made to move from one chamber to the other, and means for opening the recess in the reservoir chamber to receive a charge of liquid therefrom, and for rapidly closing ⁹⁰ said recess in the mixing chamber, to forcibly spray the charge thereinto. ⁸⁵

2. In combination in a device of the kind described, a reservoir chamber for liquid; a mixing chamber, a carrier of measured charges of liquid from one chamber to the other; comprising a rotatable disk formed of two plates, having recesses at its outer edge and means for moving the plates with respect to each other, whereby the recesses ⁹⁵ are opened and closed, for the purposes described. ¹⁰⁰

3. In combination in a device of the kind described, a reservoir chamber for liquid, a mixing chamber, a carrier of measured charges of liquid from one chamber to the other, comprising a rotatable disk having a plurality of recesses disposed about its periphery, and means for opening the recesses in the reservoir chamber, to receive charges ¹⁰⁵ of liquid therefrom, and for rapidly closing the recesses in the mixing chamber to forcibly spray the charges thereinto. ¹¹⁰

4. In combination in a device of the kind described, a reservoir chamber for liquid, a mixing chamber, a rotatable disk so disposed that its periphery moves through both chambers, means for rotating said disk, means for opening a recess at the periphery of said disk, in the reservoir chamber, to receive a charge of liquid therefrom and for rapidly closing said recess in the mixing chamber to forcibly spray the charge thereinto. ¹¹⁵ ¹²⁰

5. In combination in a device of the kind described, a reservoir chamber for liquid, a mixing chamber for the passage of air or other gas, a carrier of measured charges of ¹²⁵

liquid from one chamber to the other, comprising a rotatable member having a recess therein, means for opening the recess in the reservoir chamber to receive a charge of liquid therefrom, and for rapidly closing the recess in the mixing chamber to forcibly spray the charge thereinto.

In testimony whereof I have signed this specification in the presence of two subscribing witnesses.

JAMES M. EVANS.
